US00D958153S

(12) **United States Design Patent** (10) **Patent No.:** **US D958,153 S**
(45) **Date of Patent:** **** Jul. 19, 2022**

(54) **DISPLAY SCREEN OR A PORTION THEREOF WITH GRAPHICAL USER INTERFACE**

(71) Applicant: **Lenovo (Beijing) Co., Ltd.**, Beijing (CN)

(72) Inventors: **Yuehui Chen**, Beijing (CN); **Rui Zhao**, Beijing (CN)

(73) Assignee: **Lenovo (Beijing) Co., Ltd.**, Beijing (CN)

(**) Term: **15 Years**

(21) Appl. No.: **29/687,374**

(22) Filed: **Apr. 12, 2019**

(30) **Foreign Application Priority Data**

Oct. 12, 2018 (CN) 201830569228.1

(51) **LOC (13) Cl.** **14-04**
